BOLT-ACTION FIREARM

Carl G. Swebilius, Hamden, Conn., assignor, by
mesne assignments, to Western Cartridge Com-
pany, a corporation of Delaware

Application December 1, 1938, Serial No. 243,377

17 Claims. (Cl. 42—17)

This invention relates to improvements in bolt-action firearms and more particularly to that class of bolt-action firearms in which a bolt-operating handle swings about an axis arranged substantially-perpendicular with respect to the path of movement of the breech-bolt, though in some of its applications the present invention is not so limited.

One of the objects of the present invention is to provide a superior bolt-action firearm of the specific type above referred to in which simple, reliable, and effective construction and arrangement of parts is provided for guarding against the binding of the bolt-operating handle and associated parts during the reciprocating movement of the breech-bolt.

Another object is to provide a bolt-action firearm with superior means for releasably latching or locking the bolt-operating handle in its bolt-unlocking position.

A further object of the present invention is to provide a simple, reliable, and effective construction and arrangement of parts whereby the firing-mechanism of a bolt-action firearm is automatically rendered inoperative when the bolt-operating handle is moved into its bolt-unlocking position.

Still another object of the present invention is to provide a superior construction and arrangement of parts whereby the breech-bolt of a firearm may be securely locked in its breech-closing position by means of a bolt-operating handle swinging about an axis arranged substantially perpendicular with respect to the path of movement of the breech-bolt.

A still further object is to provide a firearm of the specific type first above referred to, in which the firing-member and breech-bolt locking-means compactly interfit.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side-elevation of a bolt-action firearm embodying the present invention;

Fig. 2 is a broken view in vertical central-longitudinal section with the barrel, breech-bolt, magazine and some of the associated parts shown

in side-elevation and with the breech-bolt in its closed and locked position;

Fig. 3 is a view corresponding to Fig. 2 save that more of the parts are shown in section;

Fig. 4 is a view substantially corresponding to Fig. 3 save that some of the parts are in side-elevation and the parts are shown in the positions which they assume when the breech-bolt is moved into its fully retired position;

Fig. 5 is a view corresponding to Fig. 4 save that the parts are shown in the positions which they assume when the breech-bolt is being moved forwardly and has reached a position slightly before its fully closed position, and the firing-pin is cocked preparatory to the discharge of the firearm;

Fig. 6 is a transverse-sectional view taken on the line 6—6 of Fig. 3;

Fig. 7 is a similar view taken on the line 7—7 of Fig. 3;

Fig. 8 is a transverse-sectional view taken on the line 8—8 of Fig. 3;

Fig. 9 is a view in side-elevation of the breech-bolt with the firing-pin unit and bolt-operating handle removed;

Fig. 10 is an under-side view thereof;

Fig. 11 is a view thereof in rear-end elevation;

Fig. 12 is a broken view of the rear portion of the breech-bolt and its operating-handle viewed from the left side and shown partly in side elevation and partly in vertical section;

Fig. 13 is a perspective view of the bolt-handle-locking member;

Fig. 14 is a similar view of the cartridge cut-off;

Fig. 15 is a perspective view of the bolt-operating handle viewed mainly from the front;

Fig. 16 is a similar view but viewing the bolt-operating handle mainly from the rear;

Fig. 17 is a perspective view of the transmitting-member of the firing-member-releasing mechanism; and,

Fig. 18 is a schematic view showing the portion of the bolt-operating handle, transmitting-member and sear, and illustrating the action of the bolt-operating handle in shifting the said transmitting-member into position for rendering the firing-member-releasing mechanism inoperative.

The particular bolt-action firearm herein chosen for the illustration of the present invention is of the take-down type and includes three major components, namely a receiver 20, a barrel 21, and a stock 22 all organized together in a manner as will more fully hereinafter appear.

The receiver 20 is cylindrically-contoured exteriorly and has its forward-end interiorly threaded for the threaded connection of the exteriorly-threaded rear-portion of the barrel 21. Extending substantially throughout its length, the receiver 20 is formed with a downwardly-opening bolt-receiving chamber 23 having its upper-half cylindrically-contoured to conform to the similarly-contoured upper-half of a reciprocating breech-bolt generally designated by the reference character 24. The said breech-bolt 24 is retained in place in the bolt-receiving chamber 23 in the receiver 20 against downward displacement therefrom, by a bar-like mounting-member generally designated by the reference character 25 and projecting upwardly slightly into the lower portion of the bolt-receiving chamber 23 in the said receiver 20 as is particularly well observable in Figs. 6 to 8 inclusive. The said bar-like mounting-member 25 includes two substantially-corresponding parallel side-plates 26 and 27 which are laterally-spaced from each other to provide a central-longitudinal channel 28, by a rear spacing-block 29 and a front spacing-block 30.

The upper portion of the rear spacing-block 29 projects above the upper surface of the side-plates 26 and 27 of the mounting-member 25 to form a head 31 which conforms in cross-sectional form to the transverse form of the bolt-receiving chamber 23 in the receiver 20. The head 31 of the spacing-block 29 is formed with a rearwardly-projecting coupling-extension 32 abutting against the rear-wall 33 of the receiver 20 and overhangs a forwardly-extending coupling-lip 34 extending forwardly from the lower portion of the said rear-wall 33, so that the said coupling-extension 32 and the said coupling-lip 34 serve to normally prevent the downward movement of the rear-portion of the mounting-member 25 from the bolt-receiving chamber 23 in the receiver 20.

The rear spacing-block 29 of the mounting-member 25 is formed at its lower portion with a rearwardly-extending coupling-lip 35 which is adapted to removably "hook-under," so to speak, a coupling-pin 36 extending transversely across the rear-portion of a longitudinally-extending upwardly-opening recess 37 formed in the stock 22, before referred to. The said coupling-pin 36 thus forms a permanent feature of the said stock 22.

Returning now to the front spacing-block 30 of the bar-like mounting-member 25 it will be noted by reference to Figs. 3, 4, and 5 in particular that the said spacing-block is formed in its forward face with a forwardly-opening cylindrical coupling-socket 38 adapted to receive the cylindrically-contoured rear-end 39 of a coupling-screw 40 located mainly beneath the rear portion of the barrel 21 and extending in parallelism therewith. The said coupling-screw 40 is threadedly-mounted in a block-like stock attaching lug 41 depending from the rear portion of the barrel 21 and fixedly attached thereto by means of a dove-tail connection 42. The stock-attaching lug 41 just referred to, has threaded into it the threaded upper end of a stock-attaching screw 43 which extends upwardly from the under-face of the stock 22 through an escutcheon 44 mounted in the said stock 22, and serves to secure the forward portion of the said stock to the barrel 21 and hence to the receiver 20 and its associated parts.

The breech-bolt 24 is formed adjacent its rear-end with a transverse bearing-passage 45 in

which is adapted to turn the cylindrically-contoured shank 46 of a bolt-operating handle generally designated by the reference character 47 and including an L-shaped arm 48 carrying at its distal end an operating-knob 49.

As above referred to the shank 46 of the bolt-operating handle 47 is, generally speaking, cylindrically-contoured but is provided with numerous cuts, notches, and projections including two clearance notches 50 and 51 respectively located in line with the side-plates 26 and 27 of the bar-like mounting-member 25 before referred to. Intermediate the clearance notches 50 and 51 just referred to, the shank 46 is formed with a forwardly-opening notch 52, the rear-wall of which constitutes a latch-engaging abutment 53 for the purpose as will hereinafter appear. Transversely in line with the notch 52 just referred to, the intermediate portion of the shank 46 is formed with a rearwardly- and downwardly-opening notch 54, the rearwardly-facing end-wall of which constitutes a limiting-abutment 55 which serves in a manner as will herein appear, to limit the rearward swinging movement of the bolt-operating handle 47.

The shank 46 of the bolt-operating handle 47 is also provided with a transverse groove 56 extending from front to rear across the upper portion of the said shank 46 and having a bottom-wall which constitutes a disconnecting-cam 57 serving in a manner as will hereinafter appear to render the firing-mechanism temporarily inoperative when the breech-bolt is unlocked, by operatively disconnecting a trigger 58 from a sear 59. The shank 46 of the handle 47 is further provided in its upper portion with a firing-pin-clearance groove 60 extending from front to rear and accommodating a reciprocating firing-plunger or -member 61 which passes from front to rear therethrough.

The firing-plunger 61 above referred to, reciprocates in an axial-passage 62 formed in the breech-bolt 24 and is formed at its forward-end with a firing-point 63 adapted to impinge against and fire a cartridge such as 64 when the same is in the cartridge-chamber 65 formed in the rear-end of the barrel 21, in the usual manner of firearms. In its upper rear-portion the said firing-plunger 61 is formed with a forwardly-facing cocking-abutment 66 which is releasably engaged by a sear-nose 67 located at the forward-end of the sear 59 which latter is mounted for pivotal movement upon a transverse pin 68 extending across a longitudinal slot 69 formed in the upper portion of the head 31 of the rear spacing-block 29 as is especially well shown in Fig. 3. The rearwardly-extending portion of the sear 59 is pressed upwardly by a helical sear-spring 70 seated in an upwardly-opening spring-pocket 71 formed in the said head 31. The sear-spring 70 as thus arranged exerts a yielding effort to hold the sear-nose 67 of the sear 59 downwardly in the path of movement of the cocking-shoulder 66 of the firing-plunger 61.

At a point intermediate the pin 68 and the sear-nose 67 the sear 59 is formed with a downwardly-facing actuating-abutment 72 which is adapted to be engaged by the upper end of the body-portion 73 of a transmitting-member generally designated by the reference character 74. The said transmitting-member 74 also includes a forwardly-extending finger 75 having its forward end bevelled to provide a forwardly- and upwardly-sloping cam surface 76 which is engageable by the disconnecting-cam 57 of the shank 46 of

the bolt-operating handle 47. The forwardly-extending finger 75 just referred to, is offset laterally out of the plane of the body-portion 73 and is integrally united therewith by a transversely-extending web 77.

The body-portion 73 of the transmitting-member 14 is mounted for both vertical reciprocating movement and rocking movement in a forwardly-opening vertical groove 78 formed in the rear spacing-block 29 and intersecting the upwardly-opening slot 69 therein as is particularly well shown in Fig. 3 of the drawings. Mounted in the rear spacing-block 29 and extending through a vertical slot 79 in the body-portion 73 of the transmitting-member 14 is a pin 80 upon which the said transmitting-member is free to rock and with respect to which the said transmitting-member is free for limited vertical movement.

Mounted in the forwardly-opening, vertical groove 78 in the rear spacing-block 29 is a helical spring 81 which exerts a constant but yielding effort to hold the transmitting-member 14 in its lowermost position and at the limit of its clockwise pivotal movement as viewed in the drawings. The lower-end of the body-portion 73 of the transmitting-member 14 is held by the spring 81 in close proximity, if not in actual contact with the upper end of the trigger 58 which is provided with a clearance-passage 82 for the purpose as will hereinafter appear. The trigger 58 is mounted for pivotal movement upon a transverse-pin 83 extending transversely across the stock 22. The said trigger 58 extends upwardly into a vertical passage 84 formed in the stock 22 and into the upper end of which passage the lower end of the body-portion 73 of the transmitting-member 14 extends.

Returning now to the bolt-operating handle 47, it will be noted that the formation of the clearance notches 50 and 51 in the shank 46 of the said bolt-operating handle, results respectively in the formation of locking-noses 85 and 86 which when turned in their unlocking positions, are adapted to ride over the upper edges respectively of the side-plates 26 and 27 of the bar-like mounting-member 25. When the breech-bolt is in its forward position and the operating-knob 49 of the bolt-operating handle 47 is swung to the limit of its forward movement the said locking-noses 85 and 86 are respectively adapted to enter locking-notches 87 and 88 respectively formed in the said side-plates 26 and 27.

When the operating-knob 49 of the bolt-operating handle 47 is drawn rearwardly such movement is limited by the engagement of the limiting-abutment 55 on the shank 46 with a forwardly-facing limiting-abutment 89 forming a feature of the breech-bolt 24. When the bolt-handle is swung as just described to engage its limiting-abutment 55 with the limiting-abutment 89, the latch-engaging abutment 53 thereof is also brought into position to be engaged by the rear-end of a pivotal bolt-handle-locking member 90. The said member 90 is mounted for rocking movement in a vertical plane in a vertically-extending groove 91 formed in the rear depending portion of the breech-bolt 24 and is pivoted in the said groove upon a transverse-pin 92 carried by the said breech-bolt.

Yieldingly urging the bolt-handle-locking member 90 to turn in a clockwise direction so as to engage its rear portion with the latch-engaging abutment 53 of the shank 46, is a helical spring 93 having its upper end seated in a shal-

low spring-pocket 94 formed in the breech-bolt 24 at the upper end of the groove 91 therein. The said spring 93 has its lower end seated in a notch 94a formed in the upper edge of the member 90. The forward portion of the bolt-handle-locking member 90 has a forwardly-and-upwardly inclined under-face or edge and constitutes a tripping-nose 95 which is adapted to engage a tripping-nose 96 formed at the rear-end of a pivotal cartridge cut-off 97 hung upon a pivot-pin 98 extending transversely between the two side-plates 26 and 27 of the mounting-member 25. At its forward end the cartridge cut-off 97 is formed with a head 99 the upper portion of which is adapted to rock upwardly into a releasing groove 100 formed in the under-face of the breech-bolt 24 and registerable with the upper portion of the said head when the said breech-bolt is in its forward or fully closed position and for a purpose as will more fully hereinafter appear.

Projecting downwardly from the head 99 of the cartridge cut-off 97 are three (more or less) cartridge-stops 101 the rearmost one of which is adapted to be engaged by and releasably hold the foremost cartridge 102 of a column of cartridges emerging from a tubular-magazine 103 under the urge of a magazine-follower 104 and a magazine-spring 105 (Fig. 3).

The said tubular-magazine 103 is normally located within a tubular-magazine-housing 106 extending downwardly and rearwardly from adjacent the cartridge cut-off 97, through the stock 22 as is shown in the drawings.

Returning now to the firing-plunger 61 it will be noted by reference to Fig. 3 in particular, that the rear-portion of the said firing-plunger is provided with a rearwardly-opening spring-receiving chamber 107 receiving the forward portion and, on occasion, the entire length of a helical firing-spring 108. The forward end of the firing-spring 108 thrusts against the front-end wall of the spring-receiving chamber 107 and thrusts at its rear-end against a thrust-shoulder 109a formed upon a guide-rod 109 at the junction of the relatively-large rear head-portion 110 thereof and the relatively-slender forwardly-extending stem 111 thereof. At its extreme rear-end the head 110 of the guide-rod 109 is formed with a rearwardly-extending boss 112 entering a socket 113 in the forward face of the rear spacing-block 29 in registry with the upper forward portion of the vertical groove 78 therein. The interfitting of the boss 112 and socket 113 serves to support the rear-end of the guide-rod 109 in alignment with the spring-chamber 107 in the firing-pin 61.

For the purpose of yieldingly holding the bolt-operating handle in its breech-bolt-locking position, the transverse bearing-opening 45 in the breech-bolt 24 has intersecting its forward periphery adjacent the left side of the said breech-bolt, a forwardly-extending plunger-receiving recess 114 in which is adapted to reciprocate a detent-plunger 115 which is pressed rearwardly by a helical spring 116 housed in the forward portion of the said plunger-receiving recess 114, as is particularly well shown in Fig. 12. In its underside, the detent-plunger 115 is formed with a limiting-notch 117 substantially corresponding in length to the desired length of the reciprocating movement of the said detent-plunger and across which extends a stop-pin 118 mounted in the adjacent portion of the breech-bolt 24. The rear end of the detent-plunger 115 slopes forwardly-and-upwardly and is adapted to engage the upper

wall 51a of the clearance-notch 51 in the shank 46 of the bolt-operating handle 47 to yieldingly hold the said bolt-operating handle in its breech-bolt-locking position.

In the manner above described, the bolt-operating handle 47 is sufficiently restrained against movement out of its breech-bolt-locking position to guard against the inadvertent unlocking of the breech-bolt by substantially all but intentionally-applied forces.

For the purpose of making clear the operation of the bolt-action firearm herein chosen for illustration of the present invention let it be assumed that the parts are in the positions in which they are shown particularly well in Figs. 1, 2 and 3 which indicate conditions prevailing after a cartridge has been fired by the forward movement of the firing-plunger 61 which has been released by the rearward-swinging movement of the trigger 58. It may be explained at this point that under normal conditions a rearward draft exerted upon the trigger 58 will cause the vertical movement of the transmitting-member 74 and the latter will in turn thrust upwardly on the actuating-abutment 72 of the sear 59 to release the said firing-plunger 61 to the action of the firing-spring 108.

If now, the user of the firearm should grasp the operating-knob 49 of the bolt-operating handle 47 and swing the same rearwardly into the position indicated by broken lines A in Fig. 1, the shank 46 of the said bolt-operating handle will be turned in a clockwise direction into the position in which it is indicated in Fig. 4. This turning of the shank 46 as just described, will engage the limiting-abutment 55 thereof with the limiting-abutment 89 of the breech-bolt 24 to thus limit the described turning movement of the said shank 46. The described turning movement of the shank 46 will also cause the disconnecting-cam 57 thereof to act through the finger 75 of the transmitting-member 74 and rock the latter into the position in which it is indicated by full lines in Fig. 18 thereby operatively-disconnecting the sear 59 from the trigger 18 so that when the firing-plunger 61 is cocked it cannot be released until such time as the bolt-operating handle 47 is in its bolt-locking position.

In addition to the above described effect of the initial clockwise turning movement of the shank 46 of the bolt-operating handle 47, the said turning movement swings the locking-noses 85 and 86 out of their complemental locking-notches 87 and 88 in the side-plate 26 and 27 respectively of the mounting-member 25, with the result that the breech-bolt 24 and the parts carried thereby are free for being retired rearwardly.

After the bolt-operating handle 47 has been turned as described in the position in which it is indicated by the broken lines A in Fig. 1 to effect the operations above described, a continued rearward draft exerted upon the operating-knob 49 will bodily shift the said bolt-operating handle 47 rearwardly into the position in which it is indicated by the broken lines B in Fig. 1 so that the parts will assume the positions in which they are shown in Fig. 4 of the drawings in which it will be noted that the breech-bolt 24 is retired to the maximum of its rearward movement and that the sear-nose 67 is located relatively forwardly of the cocking-shoulder 66 of the firing-plunger 61. As has been before noted and as will be seen by reference to Fig. 4 the shank 46

of the bolt-operating handle 47 and hence the entire handle is locked against return swinging movement by the engagement of the rear edge of the bolt-handle-locking member 90 with the latch-engaging abutment 53 of the said shank 46.

The retraction of the breech-bolt 24 above described will effect the extraction of the cartridge case of the previously-fired cartridge in the cartridge-chamber 65 of the barrel 21, in the usual manner of firearms.

If now a forward thrust is exerted upon the operating-knob 49 of the bolt-operating handle 47 the said bolt-operating handle will be prevented from turning in a counterclockwise direction by the bolt-handle-locking member 90, with the result that the said thrust upon the operating-knob 49 will become effective to forwardly-move the breech-bolt 24 and the parts carried thereby. As the said breech-bolt 24 moves forwardly the firing-plunger 61 will also move forwardly, but only for a relatively-slight distance until its cocking-shoulder 66 engages with the sear-nose 67 of the sear 69 whereupon the further forward movement of the said firing-plunger will be checked until released in a manner as will be hereinafter described.

In its forward travel as above described the front face of the breech-bolt 24 will engage the rear face of the cartridge 64 and move the said cartridge forwardly and upwardly from the position in which it is shown in Figs. 3 and 4 toward the position in which it is shown in Fig. 5, for final and full seating in the cartridge-chamber 65.

At about the time during its forward travel from the position in which it is shown in Fig. 4 that it reaches the position shown in Fig. 5, the breech-bolt 24 will have shifted the bolt-handle-locking member 90 sufficiently forwardly to engage its tripping-nose 95 with the rearwardly-projecting tripping-nose 96 of the cartridge cut-off 97 with the effect, as the said breech-bolt and the said member 90 continue to move forwardly, of rocking the said member 90 about its pin 92 in a counterclockwise direction against the tension of the spring 93. This rocking movement will completely disengage the rear end of the said member 90 from the latch-engaging abutment 53 of the shank 46 of the bolt-operating handle 47. This release of the shank 46 as just referred to occurs just as the said shank is sufficiently far forwardly for the registration of its locking-noses 85 and 86 with the locking-notches 87 and 88 respectively in the side-plates 26 and 27 of the mounting-member 25. Continued forward thrust upon the operating-knob 49 will cause the bolt-operating handle 47 to swing from the position A shown in Fig. 1 to the position shown in full lines in the same figure, thus rotating the shank 46 in a counterclockwise direction. The described movement will cause the entry of the locking-noses 85 and 86 of the shank 46 into the locking-notches 87 and 88 before referred to, to thereby firmly lock the breech-bolt in its breech-closing position. The final counterclockwise turning movement of the shank 46 of the above operating-handle 47 as just described, will cause the disconnecting-cam 57 of the said shank to turn and thereby permit the transmitting member 74, under the urge of the spring 81, to rock in a clockwise direction about its pivot-pin 80 so that the upper edge of its body-portion 73 will be located beneath the actuating-abutment 72 of the sear 59, in readiness to

rotating the shank 46 in a counterclockwise direction. The described movement will cause the entry of the locking-noses 85 and 86 of the shank 46 into the locking-notches 87 and 88 before referred to, to thereby firmly lock the breech-bolt in its breech-closing position. The final counterclockwise turning movement of the shank 46 of the above operating-handle 47 as just described, will cause the disconnecting-cam 57 of the said shank to turn and thereby permit the transmitting member 74, under the urge of the spring 81, to rock in a clockwise direction about its pivot-pin 80 so that the upper edge of its body-portion 73 will be located beneath the actuating-abutment 72 of the sear 59, in readiness to

lift the sear-nose 67 to release the firing-plunger 61 when the trigger 58 is pulled.

After the bolt-handle-locking member 90 has had its rear end cleared from the latch-engaging abutment 53 of the shank 46 of the handle 47 as above described, by the engagement of its tripping-nose 95 with the tripping-nose 96 of the cartridge cut-off 97, the slight further forward movement of the breech-bolt 24 will bring the releasing groove 100 therein into full registration with the upper portion of the head 99 of the said cartridge cut-off, thereby permitting the latter to turn in a counterclockwise direction to release the foremost cartridge 102 of the column of cartridges, for movement into a position beneath the substantially-closed forward end of the breech-bolt 24, preparatory to being fed into the cartridge chamber 65 when the breech-bolt is again withdrawn rearwardly and again moved forwardly in another cycle of the operation of the firearm. The parts will now have assumed substantially the positions in which they are shown in Fig. 3 save that the firing-plunger 61 will now be in its cocked position, as shown in Fig. 5, preparatory to discharging or firing the cartridge 64 just previously inserted into the cartridge chamber 65 of the barrel 21.

With the shank 46 of the bolt-operating handle 47 again turned to the limit of its counterclockwise turning movement so that its locking-noses 85 and 86 are again engaged with the locking-notches 87 and 88 in the side-plates 26 and 27 of the mounting-member 25, the said shank and the entire bolt-operating handle will be releasably held in this position by the coaction of the sloping rearward end of the detent-plunger 115 with the now-sloping upper wall 51a of the clearance-notch 51 in the shank 46, as is clearly shown in Fig. 12.

From the foregoing, it will be seen that by means of the bolt-handle-locking member 90 or its equivalent, the bolt-operating handle 47, when once retired rearwardly and upwardly to unlock the breech-bolt 24, is restrained in such position, so that when it is desired to again close the breech-bolt, a forward thrust exerted on the knob 49 of the said handle 27 will not turn the same to possibly cause serious jamming, friction or wear, but will cause the straight-line forward travel of the said breech-bolt until the same is closed, or substantially closed, preparatory to being locked, whereupon the said bolt-handle-locking member is automatically released at the proper time to permit the shank 46 to be turned as required for locking the said breech-bolt.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A bolt-action firearm including in combination: a breech-bolt; a bolt-operating handle having a breech-bolt-locking position and a breech-bolt-unlocking position; a firing-member; a sear for releasably holding the said firing-member in its cocked position; a trigger for releasing the said sear; a shiftable transmitting-member movable into one position wherein it is operatively interposed between the said trigger and the said

sear to transmit the movement of the former to the latter and also movable into a second position wherein it will fail to cause the release of the said sear when the said trigger is actuated; and operating-means including means respectively carried by said bolt-handle and said transmitting-member for interconnecting the same, to cause said transmitting-member to be shifted into its said second position in response to the movement of the said handle into its 10 breech-bolt-unlocking position.

2. A bolt-action firearm including in combination: a breech-bolt; a bolt-operating handle having a breech-bolt-locking position and a breech-bolt-unlocking position; a firing-member; a sear for releasably holding the said firing-member in its cocked position; a trigger for releasing the said sear; a shiftable transmitting-member movable into one position wherein it is operatively interposed between the said trigger and the said 15 sear to transmit the movement of the former to the latter and also movable into a second position wherein it will fail to cause the release of the said sear when the said trigger is actuated; and operating-means including means respectively carried by said bolt-handle and said transmitting-member for interconnecting the same, to cause said transmitting-member to be 20 positively moved into its said second position by the movement of the said bolt-operating handle 30 into its breech-bolt-unlocking position.

3. A bolt-action firearm including in combination: a breech-bolt; a bolt-operating handle having a breech-bolt-locking position and a breech-bolt-unlocking position; a firing-member; a sear for releasably holding the said firing-member in its cocked position; a trigger for releasing the said sear; a shiftable transmitting-member movable into one position wherein it is operatively interposed between the said trigger and the said 35 sear to transmit the movement of the former to the latter and also movable into a second position wherein it will fail to cause the release of the said sear when the said trigger is actuated; operating-means including means respectively carried by said bolt-handle and said transmitting-member for interconnecting the same, to cause said transmitting-member to be positively moved into its said second position by the movement of the said bolt-operating handle 40 into its breech-bolt-unlocking position; and spring-means yieldingly urging the said transmitting-member into position for transmitting the movement of the said trigger to the said sear for releasing the latter.

4. A bolt-action firearm including in combination: a breech-bolt; a bolt-operating handle having a breech-bolt-locking position and a breech-bolt-unlocking position; a firing-member; a sear for releasably holding the said firing-member in 60 its cocked position; a trigger for releasing the said sear; a transmitting-member having both rocking and reciprocating movement and rockable into one position wherein it is operatively interposed between the said trigger and the said sear to transmit the movement of the former to the latter and also rockable into a second position wherein it will fail to cause the release of the said sear when the said trigger is actuated; and operating-means including means respectively carried by said bolt-handle and said transmitting-member for interconnecting the same, to cause said transmitting-member to be rocked into its said 65 second position in response to the movement of 70 75

the said handle into its breech-bolt-unlocking position.

5. A bolt-action firearm including in combination: a breech-bolt; a bolt-operating handle having a breech-bolt-locking position and a breech-bolt-unlocking position; a firing-member; a sear for releasably holding the said firing-member in its cocked position; a trigger for releasing the said sear; a transmitting-member having both rocking and reciprocating movement and rockable into one position wherein it is operatively-interposed between the said trigger and the said sear to transmit the movement of the former to the latter and also rockable into a second position wherein it will fail to cause the release of the said sear when the said trigger is actuated; and operating-means including means respectively carried by said bolt-handle and said transmitting-member for interconnecting the same, to cause said transmitting-member to be positively moved into its said second position by the movement of the said handle into its breech-bolt-unlocking position.

6. A bolt-action firearm including in combination: a breech-bolt; a bolt-operating handle having a breech-bolt-locking position and a breech-bolt-unlocking position; a firing-member; a sear for releasably holding the said firing-member in its cocked position; a trigger for releasing the said sear; a transmitting-member having both rocking and reciprocating movement and rockable into one position wherein it is operatively-interposed between the said trigger and the said sear to transmit the movement of the former to the latter and also rockable into a second position wherein it will fail to cause the release of the said sear when the said trigger is actuated; operating-means including means respectively carried by said bolt-handle and said transmitting-member for interconnecting the same, to cause said transmitting-member to be positively moved into its said second position by the movement of the said handle into its breech-bolt-unlocking position; and spring-means yieldingly urging the said transmitting-member into position for operatively interconnecting the said trigger with the said sear.

7. A bolt-action firearm including in combination: a reciprocating breech-bolt having a breech-closing position and a breech-opening position; a bolt-operating handle oscillatable about a center substantially perpendicular with respect to the path of movement of the said breech-bolt and bodily-movable concurrently therewith, the said bolt-operating handle being swingable into a breech-bolt-locking position and into a breech-bolt-unlocking position; releasable automatic locking-means for releasably locking the said breech-bolt handle in its breech-bolt-unlocking position; and automatic releasing-means for the said releasable locking-means engageable with the latter for automatically releasing the same and hence the said handle when the said breech-bolt is moved into its breech-closing position.

8. A bolt-action firearm including in combination: a reciprocating breech-bolt having a breech-closing position and a breech-opening position; a bolt-operating handle carried by the said breech-bolt and oscillatable about a center substantially perpendicular with respect to the path of movement of the said reciprocating breech-bolt and swingable into a breech-bolt-locking position and into a breech-bolt-unlocking position; releasable automatic locking-means for releasably locking the said breech-bolt handle in its breech-bolt-

unlocking position; and automatic releasing-means for the said releasable locking-means engageable with the latter for automatically releasing the same and hence the said handle when the said breech-bolt is moved into its breech-closing position.

9. A bolt-action firearm including in combination: a reciprocating breech-bolt having a breech-closing position and a breech-opening position; a bolt-operating handle oscillatable about a center substantially perpendicular with respect to the path of movement of the said breech-bolt and bodily-movable concurrently therewith, the said bolt-operating handle being swingable into a breech-bolt-locking position and into a breech-bolt-unlocking position; releasable automatic locking-means for releasably locking the said bolt-operating handle in its breech-bolt-unlocking position; automatic releasing-means for the said releasable locking-means engageable with the latter for automatically releasing the same and hence the said handle when the said breech-bolt is moved into its breech-closing position; and spring-means yieldingly urging the said releasable locking-means into position to lock the said bolt-operating handle in its breech-bolt-unlocking position.

10. A bolt-action firearm including in combination: a reciprocating breech-bolt having a breech-closing position and a breech-opening position; a crank-like bolt-operating handle carried by the said breech-bolt and oscillatable about a center substantially perpendicular with respect to the path of movement of the said reciprocating breech-bolt and swingable into a breech-bolt-locking position and into a breech-bolt-unlocking position; releasable automatic locking-means for releasably locking the said bolt-operating handle in its breech-bolt-unlocking position; automatic releasing-means for the said releasable locking-means engageable with the latter for automatically releasing the same and hence the said handle when the said breech-bolt is moved into its breech-closing position; and spring-means yieldingly urging the said releasable locking-means into position to lock the said crank-like bolt-operating handle in its breech-bolt-unlocking position.

11. A bolt-action firearm including in combination: a reciprocating breech-bolt having a breech-closing position and a breech-opening position; a bolt-operating handle oscillatable about a center substantially perpendicular with respect to the path of movement of the said breech-bolt and bodily-movable concurrently therewith, the said bolt-operating handle being swingable into a breech-bolt-locking position and into a breech-bolt-unlocking position; releasable automatic locking-means for releasably locking the said bolt-operating handle in its breech-bolt-unlocking position; and a spring-pressed abutment engageable by the said locking-means to automatically release the same and hence the said handle when the said breech-bolt is moved into its breech-closing position.

12. A bolt-action firearm including in combination: a reciprocating breech-bolt having a breech-closing position and a breech-opening position; a crank-like bolt-operating handle carried by the said breech-bolt and oscillatable about a center substantially perpendicular with respect to the path of movement of the said reciprocating breech-bolt and swingable into a breech-bolt-locking position and into a breech-bolt-unlocking position; releasable automatic

locking-means for releasably locking the said crank-like bolt-operating handle in its breech-bolt-unlocking position; and a spring-pressed abutment engageable by the said locking-means 5 to automatically release the same and hence the said handle when the said breech-bolt is moved into its breech-closing position.

13. A bolt-action firearm including in combination: a receiver; a barrel connected to the 10 said receiver; a reciprocating breech-bolt movable in the said receiver and having a breech-closing position and breech-opening position; a magazine; a cartridge cut-off controlling the release of cartridges from the said magazine; a 15 bolt-operating handle oscillatable about a center substantially perpendicular with respect to the path of movement of the said breech-bolt and bodily-movable concurrently therewith, the said bolt-operating handle being swingable into 20 a breech-bolt-locking position and into a breech-bolt-unlocking position; and releasable automatic locking-means for releasably locking the said bolt-operating handle in its breech-bolt-unlocking position and engageable for being released by the said cartridge cut-off when the said 25 breech-bolt is moved into its breech-closing position.

14. A bolt-action firearm including in combination: a receiver; a barrel connected to the said 30 receiver; a reciprocating breech-bolt movable in the said receiver and having a breech-closing position and a breech-opening position; a magazine; a yielding cartridge cut-off controlling the release of cartridges from the said magazine; a 35 bolt-operating handle oscillatable about a center substantially perpendicular with respect to the path of movement of the said breech-bolt and bodily-movable concurrently therewith, the said bolt-operating handle being swingable into 40 a breech-bolt-locking position and into a breech-bolt-unlocking position; and releasable automatic locking-means for releasably locking the said bolt-operating handle in its breech-bolt-unlocking position and engageable for being released by the said yielding cartridge cut-off when 45 the said breech-bolt is moved into its breech-closing position.

15. A bolt-action firearm including in combination: a receiver; a barrel connected to the said 50 receiver; a reciprocating breech-bolt movable in the said receiver and having a breech-closing position and a breech-opening position; a magazine; a cartridge cut-off controlling the release of cartridges from the said magazine; a bolt- 55 operating handle oscillatable about a center sub-

stantially perpendicular with respect to the path of movement of the said breech-bolt and bodily-movable concurrently therewith, the said bolt-operating handle being swingable into a breech-bolt-locking position and into a breech-bolt-unlocking position; and a pivotal locking-member for releasably locking the said bolt-operating handle in its breech-bolt-unlocking position and engageable with the said cartridge cut-off for being rocked into its releasing position thereby when the said breech-bolt is moved into its breech-closing position.

16. A bolt-action firearm including in combination: a receiver; a barrel connected to the said receiver; a reciprocating breech-bolt movable in the said receiver and having a breech-closing position and a breech-opening position; a magazine; a yielding cartridge cut-off controlling the release of cartridges from the said magazine; a bolt-operating handle oscillatable about a center substantially perpendicular with respect to the path of movement of the said breech-bolt and bodily-movable concurrently therewith, the said bolt-operating handle being swingable into a breech-bolt-locking position and into a breech-bolt-unlocking position; and a pivotal locking-member for releasably locking the said bolt-operating handle in its breech-bolt-unlocking position and engageable with the said yielding cartridge cut-off for being rocked into its releasing position thereby when the said breech-bolt is moved into its breech-closing position.

17. A bolt-action firearm including in combination: a receiver; a barrel connected to the said receiver; a reciprocating breech-bolt movable in the said receiver and having a breech-closing position and a breech-opening position; a magazine; a pivotal cartridge cut-off controlling the release of cartridges from the said magazine; a bolt-operating handle oscillatable about a center substantially perpendicular with respect to the path of movement of the said breech-bolt and bodily-movable concurrently therewith, the said bolt-operating handle being swingable into a breech-bolt-locking position and into a breech-bolt-unlocking position; and a pivotal spring-pressed locking-member carried by the said breech-bolt for releasably-locking the said bolt-operating handle in its breech-bolt-unlocking position and engageable with the said pivotal cartridge cut-off for being released thereby when the said breech-bolt is moved into its breech-closing position.

CARL G. SWEBILIUS.
